United States Patent Office

Des. 188,323
Patented July 5, 1960

188,323

COMBINED CABLE SEPARATOR AND HANGER OR SIMILAR ARTICLE

William F. Johnson, Corning, N.Y., assignor to Corning
Glass Works, Corning, N.Y., a corporation of New
York

Filed Aug. 28, 1959, Ser. No. 57,355

Term of patent 14 years

(Cl. D26—10)

Fig. 1 is a front elevational view of a combined cable separator and hanger or similar article, showing my new design, the opposite side being substantially a mirror image thereof.

Fig. 2 is a side elevational view thereof.

Fig. 3 is a sectional view taken on line 3—3 of Fig. 1.
I claim:

The ornamental design for a combined cable separator and hanger or similar article, as shown and described.
